United States Patent Office.

THOMAS STANFORD, OF NOBLESVILLE, INDIANA.

Letters Patent No. 88,819, dated April 13, 1869.

IMPROVEMENT IN FENCES.

The Schedule referred to in these Letters Patent and making part of the same.

To all whom it may concern:

Be it known that I, THOMAS STANFORD, of Noblesville, in the county of Hamilton, and in the State of Indiana, have invented a certain new and useful Improvement in Fences; and do hereby declare that the following is a full, clear, and exact description thereof, reference being had to the accompanying drawings, and to the letters of reference marked thereon.

The nature of my invention consists in the construction and arrangement of a portable plank fence, with metal fastenings to fasten the panels together.

In order to enable others skilled in the art to which my invention appertains, to make and use the same, I will now proceed to describe its construction and operation, referring to the annexed drawings, which form a part of this specification, and in which—

Figure 1 is a perspective of the fence;

Figure 2 is a bottom view of the upper fastening; and

Figure 3, a perspective of the lower fastening.

A A represent the planks which form the panels of the fence.

B B are the posts, which are secured to the boards A A at the ends thereof, and placed alternately on the front and rear side. The ends of the boards A A are bevelled, and the outer edges come flush with the edges of the posts B B.

The panels of the fence being thus constructed, they are placed together in a zigzag form, and fastened by

means of a metal cap, C, which fits on top of the two adjoining posts.

The cap, C, is of the peculiar construction shown in fig. 2, having two recesses, or boxes, a a, in which the upper ends of the posts B B are inserted.

The lower ends of the posts B B are fastened by a metal clamp, D, (which is slipped on the posts,) having a V-shaped projection, b, which fits in the angle between the posts; and the corners of the fence being thus fastened, the fence will stand perfectly secure, and, at the same time, be easily taken apart, removed, and put up again.

Having thus fully described my invention,

What I claim as new, and desire to secure by Letters Patent, is—

1. The combination of the fence-panels A A with the cap, C, and clamp D, substantially as specified.

2. The metal cap, C, constructed as described, for the purpose of securing the upper ends of the fence-posts B B together, substantially as herein set forth.

3. The metal clamp D, constructed as described, for the purpose of fastening the lower ends of the fence-posts B B together, substantially as herein set forth.

In testimony that I claim the foregoing, I have hereunto set my hand, this 30th day of January, 1869.

THOMAS STANFORD.
